UNITED STATES PATENT OFFICE

2,281,771

GRADING MACHINE

James W. Johnston, Manchester, N. H., assignor
to North American Holding Corporation, Syra-
cuse, N. Y., a corporation of New York

Application May 24, 1940, Serial No. 336,991

15 Claims. (Cl. 69—11)

This invention relates to an improvement in grading machines for shoe soles, heel lifts, counters, taps, or other blanks of stock, and more particularly to that type of grading machine shown in the patent to Nichols No. 1,130,321, dated March 2, 1915. Although of more general application, the invention will be herein illustrated as applied to a machine of that type specifically described in the patents to Cogswell No. 1,726,610, dated September 3, 1929, and to Johnston No. 1,835,057, dated December 8, 1931. In the following specification so much of that machine will be described as is necessary for an understanding of the present invention, and reference is made to said Cogswell and Johnston patents for a more complete description. For convenience the same reference numerals so far as applicable will be applied to those elements of the machine here illustrated which were applied to corresponding elements of the machine illustrated in said Cogswell and Johnston patents.

The objects of this invention include the provision of a trip arm adapted to be actuated by the leading edge of a blank with laterally spaced fingers at opposite sides of the longitudinal center line of the machine whereby each blank, even though improperly positioned, will engage at least one finger and actuate the trip arm; the provision of latching means for the wedge bar of the grading mechanism which comprises a pair of pivotally mounted latches actuated during the advance of the blanks to positively engage and lock the slide bar so that the shifting of the wedge bar is restricted to a distance of less than one-half an inch, such latches being positively held out of contact with the wedge bar during its normal shifting in response to the thickness or thinness of the blank during the grading operation; the provision in the grading mechanism of a removable deflector associated with the skiving blade; the mounting of the delivery rollers in a housing whereby they are removable as a unit; and the provision of separable driving means for such delivery rollers.

These and other objects of the invention will appear from an examination of the following description and of the drawings which form a part thereof, and in which

Fig. 1 is a plan view of a grading machine embodying this invention;

Fig. 2 is a side elevation of such machine;

Fig. 3 is a longitudinal section thereof;

Fig. 4 is a perspective view of the trip bar by which the feeding of the blanks is controlled;

Fig. 5 is a cross-sectional view taken along 55

the line 5—5 in Fig. 1, and illustrating one face of the grading mechanism;

Fig. 6 is a perspective view of certain elements of the feeding control devices;

Figs. 7 and 8 illustrate in side and end elevations the latches for the wedge bar;

Fig. 9 is an end view of the machine taken from the right of Fig. 1, and illustrating the other face of the grading mechanism;

Figs. 10, 11, 12 and 13 illustrate elements of the driving means for the delivery rollers;

Fig. 14 is an end elevation view of the housing for the delivery rollers;

Fig. 15 is a sectional view taken along the line 15—15 in Fig. 14; and

Fig. 16 is a sectional view taken along the line 16—16 in Fig. 15.

The present invention is illustrated in a grading machine of the same general construction as those shown and described in the Cogswell Patent No. 1,726,610 and the Johnston Patent No. 1,835,057 mentioned above, and said patents are incorporated herein by reference for a fuller description of certain details which need not here be repeated in order to understand the present invention.

Referring to the drawings, the main shaft 1 which extends transversely across the machine carries at one end a pulley 2 by which the shaft is continuously driven in the direction indicated by an arrow 3 (Fig. 2) and at the other end a pinion 4 which meshes with a gear 5 on a stud shaft 6. Fixed upon the stud shaft 6 is a sprocket wheel 7 connected by a chain 8 with a sprocket wheel 9 which is loosely mounted on a shaft 10 and forms one member of a clutch which is of the well known spring-pressed type. Splined upon the shaft 10 and within the sprocket wheel 9 is a sliding clutch sleeve 11 which is normally held at rest and out of clutching engagement with the sprocket wheel 9 by a shipper 12. The shipper 12 is in the form of an arm pivotally mounted intermediate its ends upon a stud 13 and normally held by a spring 14 in engagement with a pin 15 carried by the sleeve 11. A set screw 16 adjustably fixes such position of the shipper. Through means to be described below, the shipper 12 is disengaged from the pin 15 and a single rotation of the shaft 10 permitted in a clockwise direction (Fig. 2).

The blanks S are fed one at a time from a hopper by a feed slide (not shown) actuated through a link 17 by a crank arm 18 fixed to the inner end of the shaft 10 between the side walls of the frame. At the outlet of the hopper is

mounted a U-shaped grate 20 pivotally supported at its ends at 21 and raised by the advanced end of the blank being fed. This feeding mechanism is more fully described in the Cogswell patent above mentioned.

The blank then enters between the initial pair of detector rolls 25 and 26. The upper roll 25 is continuously driven from the shaft 6 by a gear 27 compounded with the gear 5 and a gear 28 on the shaft of the roll. The lower roll 26 is driven from the upper roll 25 through intermeshing gears and yieldably urged into contact therewith as by the construction fully shown and described in the above-mentioned Johnston patent.

The detector rolls 25 and 26 advance the blank into position between the usual spring actuated hold-down shoe 30 and a feed chain 31. The feed chain 31 is continuously driven by a shaft 32 actuated from the main shaft 1, in the direction indicated by the arrow 33 on Fig. 3, and its upper run travels in a groove in the table 35. As the blank moves into this position its leading edge engages the inclined fingers 36 of a trip bar 37 pivoted at 38 upon the shoe 30 and swings such bar upwardly.

It will be noted (Fig. 1) that the fingers 36 are spaced laterally so that they straddle the shoe 30 and normally rest upon the table 35 at each side of the longitudinal center line of the machine. It is the usual practice to construct the hopper H of machines of this type with movable side walls capable of manual adjustment separately in accordance with the width of the blanks and as a unit to bring the longitudinal center line of the hopper into the longitudinal center line of the machine. Should such adjustment not be properly carried out, the blank will enter the machine at one side or the other of such center line. By providing two fingers 36, one at each side of the longitudinal center line, a blank thus improperly positioned will engage at least one of the fingers 36 and thus trip the bar 37.

Extending transversely of the machine is a lever arm 40 (Figs. 1, 3 and 6) which is pivoted at one end at 41 upon the frame of the machine and rests upon and is supported by the free end of the trip bar 37 directly above the fingers 36 (see Fig. 3). The lever bar 40 acts through the following mechanism to control the rotation of the shaft 10 and thereby the feeding of the blanks S. A link 42, pivoted at its upper end to the other end of the lever arm and suspended therefrom, has a slot 43 through which passes a bar 44. The bar 44 is pivoted at one end to the frame of the machine by a stud 45 in alignment with the pivoted ends of the gate 20. A latch bar 46 is pivoted at its upper end to and depends from the bar 44. The latch bar 46 is provided with a shoulder 47 which, when the latch bar is raised by the tripping of the trip bar 37, is swung by the spring 48 to the left in Fig. 2 above the tail 49 of the shipper 12.

As the rear edge of the blank S, that has raised the trip bar 37, passes beyond the fingers 36 the trip bar drops to its former position, whereupon the lever bar 40 drops, lowering the bar 44 and latch bar 46 and causing the shipper 12 to release the clutch sleeve 11 so that the clutch is set and the shaft 10 is rotated. The feeding of another blank S from the hopper thereupon is initiated. As the shaft 10 is rotated in a clockwise direction the pin 15 trips one end of an arm 49 pivotally mounted upon

the frame and yieldably held by a spring 50 with that end in the path of travel of the pin and the other end adjacent the lower end of the latch bar 46 so that the shipper 12 is released 5 and will engage the pin 15 to stop the rotation of the shaft 10 at the completion of a single revolution.

In order to start the machine when at rest a starter 51 is provided by which the lever bar 40 can be raised manually. Such starter 51 (see Fig. 6) is so mounted upon the frame, as by screws 55 passed through longitudinally extending slots 56, that it is freely reciprocable. The lower end is bent back upon itself to form 15 a loop 57 enclosing the lever bar 40 and the upper end bent outwardly to provide a handle 58. The screws 55 and slots 56 are so located that the starter normally takes the lowest position in which the lever bar 40 rests in the loop. The 20 raising of the starter obviously raises the lever bar and through the mechanism just described initiates the feeding of the blanks S. The bar 44 is guided by a bracket 59 mounted upon the frame and having a vertical slot therein which receives and guides the free end of the bar.

In accordance with the disclosure in the patents previously mentioned the measurements or thickness detections as determined by the detecting roll 26 are transmitted to the wedge bar 155 and thence to the grading mechanism (that is, the skiving or evening device 60 and the marking wheel 175) by suitable mechanism such as that disclosed in the said Cogswell Patent No. 1,726,610.

The passage of a blank between the detecting rolls 25 and 26 causes the lower roll 26 to move up and down in response to the thickness and thinness of parts of the blank. Such movement is transmitted to the rock shaft 139 and thence to the wedge bar 155 and marking wheel 175 by mechanism similar to that fully described in said Cogswell Patent No. 1,726,610. Mounted upon the rock shaft 139 are opposed ratchet segments 163 and 164. A pawl 165 normally meshes with the segment 163 while a pawl 166 is adapted to mesh with the segment 164 but is normally out of engagement therewith. The pawl 165 is so connected by lever 54 and link 53 with the gate 20 that when the gate is raised 45 by a blank in progress, the pawl is raised out of mesh and the shaft 139 is freely movable in either direction.

As the blank is advanced by the chain 31 its leading edge trips and raises shoes 174 adjustably clamped to the arm 173 and acting through shaft 171, arm 170 and push rod 169 to allow the pawl 166 to mesh with the ratchet segment 164. The shaft 139 is now held against movement in a direction corresponding to the thicker measurements of the blank but is free to move in the other direction in response to successively thinner measurements. When the rear edge of the blank passes from under the gate 20 the latter falls and the pawl 165 resumes its normal position. The rock shaft 139 is now locked against movement in either direction until the rear edge of the blank passes from under the shoe 174 and allows the pawl 166 to resume its normal inoperative position.

The marking wheel 175 (Fig. 5) is actuated by a gear segment 186 pivotally mounted upon a slide 185 on which the wheel is rotatably mounted. The segment 186 is connected to the wedge bar 155 by an arm 187 (Fig. 1) fixed to one end of the bar and a link 188 so that the

wheel is set in unison with the wedge bar. Means about to be described are provided by which the wedge bar 155 and marking wheel 175 are locked in the final adjusted position until the blank, whose measurements determine the setting of the wedge bar and the marking wheel, has passed the grading devices.

A plate 200 carried at one end by the arm 187 (Fig. 1) is slidably supported upon the frame by a stud 201 (Fig. 5) passed through a slot 202. At the lower edge of the plate 200 is provided a rack comprising teeth 203 separated by spaces 204 of the same width as the teeth. The dimensions of the rack are such that the distance from the center of one tooth to the center of the adjacent tooth is equal to the displacement of the wedge bar 155 due to a predetermined variation measured in irons in the thickness of the blank. For example, such distance may correspond to a one-iron displacement of the lower detecting roll 26. Preferably the distance will correspond to a predetermined multiple of one iron; thus, if the amplification be that of one to six, the distance between centers would be one-eighth of an inch and the width of each tooth and of the spaces 204 between the teeth would be one-sixteenth of an inch.

Pivottally mounted upon the frame are a pair of latches 205 carried by a stud 206 upon a bracket 207 and yieldably held by springs 208 with the upper ends in contact with the plate 200 at the row of teeth 203. The upper end of each latch is formed to provide a tongue 210. Each tongue is of the same width as the teeth 203, for example one-sixteenth of an inch, and the tongues are in contact as shown in Fig. 7. The bracket 207 is Z-shaped in form and has a slot 211 through which the upper ends of the latches project and by which the latches are guided in movement. The lower ends of the latches are tapered and extend in front of the bar 44 which terminates in an enlarged nose or cam 212.

When, during the advance of the blank below the shoe 30 the bar 44 is raised by the mechanism previously described, the cam 212 engages the lower ends of the latches 205 and retracts the upper ends thereof from contact with the plate 200. When, however, the blank permits the trip bar 31 to drop and the bar 44 is lowered, the cam 212 moves out of contact with the latches 205 and the springs 208 advance the upper ends of the latches into contact with the rack on the bar 200. In the great majority of cases the tip of one of the latches will enter one of the spaces 204 between the teeth 203 in the rack so that the plate 200 is held against movement and the wedge bar 155 accordingly locked in place. Even if the plate 200 be so positioned that neither latch enters a space 204, the possible movement of the plate is limited; thus in the present installation such movement is necessarily less than one-half an iron.

As the blank S is advanced toward the grading mechanism the leading edge actuates trip bars 89 which cause the wheel 175 that has been set by the rock shaft 139 to descend and place a mark upon the portion of the blank now resting upon the anvil 90. Such operation is performed by mechanism not here shown since it forms no part of the present invention, but fully disclosed and described in the said Cogswell Patent No. 1,726,610.

The leading edge of the blank now enters the bite of the feed rollers 61 and 62 of the skiving device 60. The feed rollers are positively driven

from the main shaft 1, the upper roller 61 through a gear 63 on that shaft, and a gear 64 on the shaft of the roller, and the lower roller 62 through the gear 4 and a gear 65 on the shaft of that roller. The journal boxes 66 and 67 of the rollers are slidably mounted in ways so that upon the insertion of the blank the upper roller 61 is raised until the wedges 157 on the journal boxes 67 come in contact with the wedges 155 on the wedge bar 155, while the lower roller 62 is forced downwardly against the supporting pressure of springs 176.

The blank is fed by the rollers 61 and 62 against the cutting edge of a knife 71 fixed upon the machine by which the surplus or waste stock is removed. The distance that the upper roller is raised, which is controlled by the wedge bar 155 in response to the action of the detector rolls, determines the final thickness of the blank while the distance that the lower roller is depressed determines the thickness of the layer to be removed. Preferably the blanks are fed with the flesh side down so that the portion removed is taken from that side.

While the surplus portion or skiving is directed downwardly by the knife blade 71, the skived blank is directed by the blade and a deflector 72 into the bite of constantly driven delivery rollers 80 and 81. The deflector 72 comprises a substantially horizontal plate 73 above and spaced from the blade. The plate is carried between a pair of legs 74 which rest upon the frame of the machine at opposite sides of the blade 71. Above the plate 73 project lugs 75 which carry set screws 76. By tightening the set screws against the frame the deflector 72 is thus held firmly in position. When it is desired, the deflector may easily be removed to afford free access to the skiving blade.

The delivery rollers 80 and 81 are enclosed within a housing 82 and are removable as a unit away from the end of the machine. The housing 82 is supported upon a U-shaped bracket 83 fixed to the end of the machine frame and is pivotally secured to the bracket by a spindle 84 projecting downwardly from one end of the housing and passing through openings in the end plates of the bracket. The housing is removably secured in position by a plate 85 fixed to the other end of the housing and having an opening 86 therein which, when the unit is in position, receives one end of a latch bar 87 carried by the machine frame and slidably transversely thereof. The free end of the unit rests upon a roller 88 carried by a bracket fixed to the machine frame, which roller is engaged by the edge of the plate 85 as shown in Fig. 2.

The housing 82 comprises a U-shaped base 95 and a top plate 96 which surround the rollers (see Fig. 14). Each end wall 97 is cut away to provide a pocket 98 which receives the journal boxes 99 and 100 that carry the shafts 101 and 102 of the rollers 80 and 81, respectively (see Fig. 15). The journal boxes 100 are stationary and rest in the bottom of the pockets. The journal boxes 99 are reciprocably in the pockets and are guided by shoulders 103 on the journal boxes which engage shoulders 104 on the walls of the pockets. The journal boxes 99 are yieldably held in contact with the journal boxes 100 by the following mechanism: Secured to the bottom of each box 99 is a crossbar 105 against the ends of which abut the bottoms of spiral springs 106 which extend at each side of the box. The tops 75 of the springs are connected by a crossbar 107.

Portions of the pocket wall and of the box 99 are cut away to provide chambers which receive the springs 106 and the ends of the cross-bars 105 and 107 (see Figs. 15 and 16). A set screw 108 acts upon the crossbar 107 and regulates the tension of the springs 106. A disk or washer 109 may be inserted, if desired, between the crossbar 105 and the journal box 100. Suitably formed guard plates 110 and 111 substantially close the sides of the housing.

Since the delivery rollers are mounted in the housing 82 and movable toward and from the operating position, the means for driving the rollers must be such as to permit that movement of the housing. When the delivery rollers 80 and 81 are set in the position shown in Figs. 1, 2 and 3, they are continuously rotated by a sprocket 115 on the shaft of the lower roller 62 of the skiving device 60, through a chain 116 and a sprocket 117. The hub 118 of the sprocket is journaled in a bearing 119 supported by a post 120 carried by the bracket 83 and secured therein by a collar 121. A shaft 122 is reciprocal in the hub 118 and is rotated thereby through fins 123 on the spindle, which are received in slots 124 in the hub 118. The latch bar 87 carries at its outer end an arm 125 having an opening therein which receives the shaft 122. Collars 126 fixed to the shaft at opposite sides of the arm hold the latter in position on the spindle. The shaft 102 of the lower roller 81 is in alignment with the hub 122 when the delivery unit is in the operable position. The end of the shaft 102 adjacent the shaft 122 is provided with a thimble 127 having diametrically opposed notches 128.

Through the construction thus described it will follow that the advance of the latch bar 87 to secure the housing to the machine frame advances the shaft 122 in the hub 118 until the fins 123 enter the notches 128 in the thimble 127 so that the rollers 80 and 81 will be rotated, while the retraction of the latch bar to release the housing will also retract the shaft 122 so that the fins 123 are withdrawn from the notches 128 and the housing may be swung on the spindle 84 away from the machine frame.

The operation of the illustrated machine will now be briefly described. The lowest blank S in the hopper H is fed under the grate 20 between the detector rolls 25, 26 onto the feed chain 31 below the hold-down shoe 30 and into contact with the fingers 36 of the pivotally mounted strip bar 37 thereby swinging such bar upwardly. This movement of the bar 37 lifts the lever bar 40 and the latter raises the bar 44. The cam 212 on the bar 44 engages the lower ends of the latches 205 and moves their outer ends out of contact with the teeth 203 of the plate 200 of the grading mechanism and permits the setting of such mechanism in response to the movement of the detector roll 26. When the blank has passed out of engagement with the fingers 36 of the trip bar 37, the latter resumes its normal position and allows the lever bar 40 and bar 44 to do likewise. The latch 46 pivoted at its upper end to the bar 44 thereupon trips the shipper 12 to permit rotation of the shaft 10 and the feed of the next blank. The cam 212 at the same time releases the latches 205 which thereupon lock the grading mechanism as set by the 70 detecting mechanism. The blank having received its grade mark enters the bite of the feed rollers 61 and 62 of the skiving device 60 by which it is fed against the cutting edge of the knife 71 by which the surplus stock is removed 75

while the blank continues below the deflector 12 to the delivery rollers 80 and 81 by which it is removed from the machine.

Unless otherwise required by the context the term "grading mechanism" is used herein generally as explained in said Cogswell Patent No. 1,726,610.

It should be understood that the present disclosure is for the purpose of illustration only and 10 that this invention includes all modifications and equivalents which fall within the scope of the appended claims.

I claim:

1. A grading machine which comprises detecting mechanism, grading mechanism settable responsive to the detecting mechanism, and means governing the admission of blanks to the detecting mechanism and the locking of the grading mechanism, characterized in that said grading mechanism including a slideable wedge bar and a plate carried thereby and movable therewith, said plate having a rack on one face thereof formed by teeth and spaces between the teeth, all said teeth and spaces being of the same width, and said governing means including a pair of pivotally mounted latches which normally engage said plate and hold said wedge bar at rest and a bar by which said latches are held out of such engagement during the setting of the grading mechanism responsive to the detecting mechanism.

2. A grading machine which comprises detecting mechanism, grading mechanism settable responsive to the detecting mechanism, and means governing the admission of blanks to the detecting mechanism and the locking of the grading mechanism, characterized in that said grading mechanism including a slideable wedge bar and a plate carried thereby and movable therewith, said plate having a rack on one face thereof formed by teeth and spaces between the teeth, all said teeth and spaces being of the same width, and said governing means including a pair of pivotally mounted latches which normally engage said plate and hold said wedge bar at rest and a bar by which said latches are held out of such engagement during the setting of the grading mechanism responsive to the detecting mechanism, the bar engaging portions of the latches being of the same width as the teeth and spaces and being so associated that the latches engage only one tooth and the space adjacent thereto.

3. A grading machine of the kind having detecting mechanism, grading mechanism responsive to the detecting mechanism, and means governing the admission of blanks to the detecting mechanism, characterized in the provision of means controlled by a blank in progress from the detecting mechanism to the grading mechanism whereby the governing means are actuated to feed a succeeding blank and the grading mechanism is simultaneously locked, which blank-controlled means include a trip bar having laterally spaced fingers at opposite sides of the longitudinal center line, one at least of which fingers is engaged by the leading edge of the blank in progress to raise said trip bar and is released by the trailing edge of such blank.

4. A grading machine of the kind having detecting mechanism, grading mechanism responsive to the detecting mechanism, and means governing the admission of blanks to the detecting mechanism, characterized in the provision of means controlled by a blank in progress from

the detecting mechanism to the grading mechanism whereby the governing means are actuated to feed a succeeding blank and the grading mechanism is simultaneously locked, which blank-controlled means include a trip bar having laterally spaced fingers at opposite sides of the longitudinal center line, one at least of which fingers is engaged by the leading edge of the blank in progress to raise said trip bar and is released by the trailing edge of such blank, a pivotally mounted bar actuated by the trip bar in response to the travel of a blank, and a pair of latches by which said grading mechanism is locked, said latches being held by said pivotally mounted bar in the inoperative position until said trip bar is released by the trailing edge of the blank whereupon one only of said latches acts to lock said grading mechanism.

5. A grading machine of the kind having detecting mechanism, grading mechanism responsive to the detecting mechanism, and means governing the admission of blanks to the detecting mechanism, characterized in the provision of means controlled by a blank in progress from the detecting mechanism to the grading mechanism whereby the governing means are actuated to feed a succeeding blank and the grading mechanism is simultaneously locked, which blank-controlled means include a trip bar having laterally spaced fingers at opposite sides of the longitudinal center line, one at least of which fingers is engaged by the leading edge of the blank in progress to raise said trip bar and is released by the trailing edge of such blank, a pivotally mounted bar actuated by the trip bar in response to the travel of the blank, and a pair of latches pivotally mounted intermediate their ends and by which said grading mechanism is locked, said latches being engaged by one end of said pivotally mounted bar and swung into inoperative position, in which position the latches are held until said trip bar is released by the trailing edge of the blank, whereupon the latches are released and one only acts to lock said grading mechanism.

6. A grading machine of the kind having detecting mechanism, grading mechanism responsive to the detecting mechanism, and means governing the admission of blanks to the detecting mechanism, characterized in the provision of means controlled by a blank in progress from the detecting mechanism to the grading mechanism whereby the governing means are actuated to feed a succeeding blank and the grading mechanism is simultaneously locked, which blank-controlled means include a trip bar having laterally spaced fingers at opposite sides of the longitudinal center line, one at least of which fingers is engaged by the leading edge of the blank in progress to raise said trip bar and is released by the trailing edge of such blank, a bar pivotally mounted adjacent one end and provided with a cam at the other end thereof, said bar being actuated by said trip bar in response to the travel of the blank, and a pair of latches pivotally mounted intermediate their ends and by one end of which said grading mechanism is locked, the other ends of which latches are engaged by the cam of said pivotally mounted bar to swing the other ends thereof into inoperative position, in which position the latches are held until said trip bar is released by the trailing edge of the blank, whereupon the cam is moved out of engagement with the latches to

release said latches and permit one only of said latches to lock said grading mechanism.

7. In a machine of the class described wherein blanks are fed through the machine and operated upon during their progress by power driven mechanism, which machine includes delivery rollers by which the blanks are discharged, a housing in which rollers are mounted, said housing being stationed at the end of the machine when the rollers are in operating position and being removable therefrom when desired, and means carried by the machine by which the rollers are operated when the housing is so stationed, said means being separable from the rollers prior to the removal of the housing from the machine.

8. In a machine of the class described wherein blanks are fed through the machine and operated upon during their progress by power driven mechanism, which machine includes delivery rollers by which the blanks are discharged, a housing in which rollers are mounted, said housing being stationed at the end of the machine when the rollers are in operating position and being removable therefrom when desired, and means for driving said rollers from the source of power of said mechanism.

9. In a machine of the class described wherein blanks are fed through the machine and operated upon during their progress by power driven mechanism, which machine includes delivery rollers by which the blanks are discharged, a housing in which rollers are mounted, said housing being stationed at the end of the machine when the rollers are in operating position and being removable therefrom when desired, and means for driving said rollers from the source of power of said mechanism, said means being separable whereby the rollers are disconnected from the source when the housing is free for removal from the frame of the machine.

10. In a machine of the class described wherein blanks are fed through the machine and operated upon during their progress by power driven mechanism, which machine includes delivery rollers by which the blanks are discharged, a housing in which rollers are mounted, said housing being stationed at the end of the machine when the rollers are in operating position and being removable therefrom when desired, means actuated by the source of power of said mechanism for driving said rollers, said means including separable connecting elements, and a latch for removably securing the housing to the frame of the machine with the rollers in operating position.

11. In a machine of the class described wherein blanks are fed through the machine and operated upon during their progress by power driven mechanism, which machine includes delivery rollers by which the blanks are discharged, a housing in which rollers are mounted, said housing being stationed at the end of the machine when the rollers are in operating position and being removable therefrom when desired, means actuated by the source of power of said mechanism for driving said rollers, said means including separable connecting elements, and a latch for removably securing the housing to the frame of the machine with the rollers in operating position, said latch including an element associated with said separable connecting elements by which said elements are united when the latch secures the housing to the frame and are separated when the latch releases said housing from the frame.

12. In a machine of the class described wherein blanks are fed through the machine and operated upon during their progress by power driven mechanism, which machine includes delivery rollers by which the blanks are discharged, a housing in which rollers are mounted, said housing being stationed at the end of the machine when the rollers are in operating position and being removable therefrom when desired, means actuated by the source of said mechanism for driving said rollers, said means including separable connecting elements, and a latch bar carried by the frame of the machine for reciprocation transversely thereof and adapted to engage said housing and secure it with the rollers in 15 operating position.

13. In a machine of the class described wherein blanks are fed through the machine and operated upon during their progress by power driven mechanism, which machine includes delivery rollers by which the blanks are discharged, a housing in which rollers are mounted, said housing being stationed at the end of the machine when the rollers are in operating position and being removable therefrom when desired, means actuated by the source of said mechanism for driving said rollers, said means including separable connecting elements, and a latch bar carried by the frame of the machine for reciprocation transversely thereof and adapted to engage 30 said housing and secure it with the rollers in operating position, and an arm carried by said latch bar and by which the connecting elements are joined when the housing is engaged by the latch bar and separated when the housing is released by said latch bar. 35

14. In a machine of the class described wherein blanks are fed through the machine and operated upon during their progress by power driven mechanism, which machine includes delivery rollers by which the blanks are discharged, a housing in which the rollers are mounted, said housing being pivotally mounted upon the frame of the machine and movable into and out of operating position, and means actuated by the source of power of said mechanism for driving said rollers when in operating position, said means including a connecting element carried by the frame and movable into engagement with a shaft of one of said rollers.

15. In a machine of the class described wherein blanks are fed through the machine and operated upon during their progress by power driven mechanism, which machine includes delivery rollers by which the blanks are discharged, a housing in which the rollers are mounted, said housing being pivotally mounted upon the frame of the machine and movable into and out of operating position, a latch bar carried by the frame of the machine and movable transversely thereof for securing the housing in operating position, means actuated by the source of power of said mechanism for driving said rollers when in operating position, said means including a connecting element carried by said frame and movable into engagement with a shaft of one of said rollers, and an arm carried by said latch bar by which said element is moved into such engagement when the latch bar is moved to secure the housing in operating position.

JAMES W. JOHNSTON.
